UNITED STATES PATENT OFFICE.

MARTIN MADSEN, OF MONTEREY PARK, CALIFORNIA.

OIL AND GAS BURNER.

Application filed February 25, 1926. Serial No. 90,466.

My invention has to do with a novel burner suitable for use in ranges, stoves, furnaces and the like, and is constructed for using either oil or gas as a fuel. In certain types 5 of ranges such as are employed in restaurants, it is highly desirable that the entire grid be heated to a uniform temperature. In the ordinary form of burner an even heating of the grid is not obtained, since these burners tend to produce localized heat.

It is an important object of this invention to provide a burner which will evenly distribute heat over the entire area of a grid. The burner of my invention employs a secondary air passage to which I attribute much 15 of the even distribution of heat. This secondary air passage supplies air which accomplishes a sort of secondary combustion when it mixes with the fuel.

It is another object of my invention to provide a burner of this character which is very efficient in operation, but which is cheap 20 to produce and may therefore be offered to the public at a low price.

Other objects and advantages of this invention will be manifested hereinafter.

Referring to the drawing in which I illustrate a preferred embodiment of my invention,

Fig. 1 is a section through a range employing a burner of this invention.

Fig. 2 is an enlarged fragmentary section of the forward end of the range of Fig. 1 and showing clearly the details of my invention.

Fig. 3 is a front view taken as indicated by the arrow 3 of Fig. 2, this view being partially sectioned to show certain details.

Fig. 4 is a section taken substantially as indicated by the line 4—4 of Fig. 2 and in the direction of the indicating arrows.

The form of my invention shown in the drawing is adapted to be used in a range 11 having a combustion chamber 12 which is situated below a grid 13. Gases of combustion are withdrawn from the combustion chamber 12 at the rear part thereof through a vent pipe 14. At the forward part of the combustion chamber 12 there is an enlarged 45 part 15. The forward part of the part 15 of the combustion chamber 12 is divided into a plurality of burner compartments 17 by means of partitions 18. The burner compartments 17 communicate with the exterior 50 of the range 11 by means of mouths 19.

In each burner compartment 17 there is

placed a burner 20 embodying the features of this invention. Each burner 20 has a body 21 which has a lower wall 22 which extends along the bottom of the burner compartment 17 and is curved upwardly at 23 as illustrated in Fig. 2. The body 21 is also provided with a septum plate 25 which extends parallel to the bottom wall 22 and is spaced a distance thereabove. The septum plate 25 divides the mouth 19 into a primary draft passage 27 and a secondary draft passage 28. The secondary draft passage 28 communicates with the combustion chamber 12 through an opening 29 formed between the end of the septum plate 25 and the upward curved end 23 of the bottom wall 22. The septum plate 25 and the lower wall 22 are connected together by vertical side walls 31. At the forward part of the body 21 and at opposite sides thereof are vertical legs 32 which are adjacent to the partitions 18. Extending outwardly from the legs 32 and the forward part of the body 21 are flanges 33 which engage a front wall 34 of 80 the range 11. Bolts 36 are provided for securing the body 21 in place, these bolts 36 extending through the flanges 33 and into the front wall 34 of the range 11.

Positioned above the mouth 19 is a head 85 38 of the burner 20. A portion 39 of rectangular cross section of the head 38 rests in a cavity 40 directly above the mouth 19. The portion 39 is provided with a fuel chamber 42. Fuel is supplied to the chamber 42 90 through a passage 43 which is formed in a projection 44. A pipe 45 having a valve 46 is connected to the outer end of the projection 44, this being best illustrated in Fig. 2.

A plurality of threaded openings 48 which 95 connect with the fuel chamber 42 is formed through a lower wall of the portion 39 of the head 38. Screwed into these threaded openings 48 are threaded extensions 50 of nozzles 51. The nozzles 51 have heads 52 100 which project vertically downward into the primary draft passage 27. An orifice 53 is formed in each of the nozzles 51, each orifice 53 connecting to the chamber 42 and also connecting to the primary draft passage 27. 105 As illustrated in Fig. 2, each orifice 53 has a horizontal portion which connects with a vertical portion so that fuel is directed horizontally into the primary draft passage 27 in the direction of the passage of air there-through.

Secured to the front of the burner is a

shell or hood 55 having a curved front wall 56 and plane side walls 57. Extending outwardly from the side walls 57 are flanges 58 through which outer portions of the bolts 36 extend. Openings 59 are provided in the flanges 58 through which the bolts 36 extend, these openings being enlarged at the lower ends thereof so that the heads of the bolts 36 may pass therethrough when the shell 55 is raised and moved outwardly, this permitting the removing of the shell 55. The shell 55 is provided so that air drawn through the primary and secondary draft passages 27 and 28 will be taken from above.

15 The operation of my invention is as follows:

As stated in the preamble, the burner of my invention may use either an oil or gas as a fuel. This fuel is supplied through the 20 pipe 45 to the chamber 42 when the valve 46 is opened. The fuel, which we will assume is gas in this instance, passes through each of the nozzles 51 into the primary draft passage 27. The gas issues from the nozzles 51 in the form of streams which are directed horizontally and which tend to produce a draft. This gas passes into the large part 25 of the combustion chamber where it may be ignited.

30 The gas is quite thoroughly mixed with the air passing through the primary draft passage 27 and a comparatively efficient combustion takes place in the enlarged part 15 of the combustion chamber 12. A passage of 35 air is established through the secondary draft passage 28, this passage of air flowing as indicated by arrows 60. It should be noted that this flow of air tends to confine itself to the area of the combustion chamber 12. 40 A passage of air is established through the secondary draft passage 28, this passage of air flowing as indicated by arrows 60. It should be noted that this flow of air tends to confine itself to the area of the combustion chamber 12. 45 Reached, the secondary flow of air, that is, the flow of air passing through the secondary draft passage 28 is thoroughly mixed with the gas and a sort of secondary combustion takes place. In other words, the primary 50 flow of air which flows through the primary draft passage 27 mixes immediately with the gas upon its entrance into the burner compartments 17, there being a plurality of these, as indicated in Figs. 3 and 4, and 55 supports combustion in the forward part of the combustion chamber 12. The secondary flow of air does not mix with the gas at the extreme forward part of the combustion chamber 12, but mixes with it at the central 60 and rear parts thereof. This supports combustion at the rear part of the combustion chamber, and gas which would not ordinarily be used is burned in the rear part of the combustion chamber 12.

65 In actual experience I have found that

the burner of my invention is extremely effective in equally distributing heat over the grid 13 and that at any point thereon the temperature is substantially the same as at any other point. This is a desirable advantage, since it renders more area of the grid 13 utilizable in cooking than would be possible if there were only localized heated areas of the grid such as is the case in ordinary burners. The burner of my invention 70 I find is highly efficient and I believe that this results from a very thorough mixing of gas and air. It is thought that this thorough mixing is accomplished by extending the nozzles 51 into the primary draft 75 passage 27 and by directing the gas or fuel 80 in a direction of the flow of air therethrough.

As previously mentioned the shell 55 of each burner is provided so that this burner will take air only from an upward direction. I have found in ranges employing an oven that, when the oven is opened, smoke therefrom (when the shell 55 is not provided) is drawn through the draft passages 27 and 28, 90 interfering with the operation of the burner. With the shell 55 in place, all this difficulty is eliminated.

When using oil or distillate as a fuel, this distillate is supplied to the body in the same 95 manner as in the case of the gas. However, the horizontal portion of the orifices 55 in the nozzle 51 are made somewhat smaller so that more of a spray effect is produced. When using distillate as a fuel it is necessary 100 to prime the burner. This is accomplished by forming the body of distillate above the lower wall 22 of the body 21. As illustrated in Figs. 1 and 2, the forward part of the lower wall 22 is provided with a lip 105 61 which makes it possible to retain liquid thereon. This body of priming liquid is ignited and the septum plate 25 which serves also as a generating plate is heated, and as 110 distillate is supplied through the nozzles 51 it is vaporized and the igniting thereof immediately takes place. This volatilized distillate, of course, mixes with the air in the same manner as the gas, and practically 115 the same action as in the case of using gas as a fuel takes place when distillate is used.

From the foregoing description it is notable that one important feature of my invention resides in the fact that the burner of my invention has what we may consider 120 a primary and secondary stage of combustion, and because of this the burner is effective in distributing a uniform heat to all portions of the grid 13. Another important feature of the invention is its efficiency 125 which is thought to be effected by the arrangement of the nozzles 51 and the primary and secondary draft passages 27 and 28. Since the passage of air through the secondary draft passage 28 mixes with an un- 130

used gas at the rear part of the combustion chamber 12 and allows it to ignite, there is an increase of efficiency.

I claim as my invention:

5. 1. In a burner, the combination of: walls forming a combustion chamber, and a mouth connecting said combustion chamber to the exterior; a body situated in said mouth, and extending a considerable distance into said 10 combustion chamber, said body dividing said mouth into a primary draft passage communicating directly with the forward portion of said combustion chamber, and a secondary draft passage communicating directly with said combustion chamber rearwardly of said primary passage; a body disposed above said mouth; and a nozzle carried by said last-named body, said nozzle projecting into said primary passage for supplying 15 fuel thereto.

2. In a burner, the combination of: walls forming a combustion chamber, and a mouth connecting said combustion chamber to the exterior; a body situated in said mouth, 25 and extending a considerable distance into said combustion chamber, said body dividing said mouth into a primary draft passage communicating directly with the forward portion of said combustion chamber, and a 30 secondary draft passage communicating directly with said combustion chamber rearwardly of said primary passage; a body disposed above said mouth; and a nozzle carried by said last-named body, said nozzle projecting vertically into said primary 35 passage for supplying fuel thereto.

3. In a burner, the combination of: walls forming a combustion chamber, and a mouth connecting said combustion chamber 40 to the exterior; a body situated in said mouth, and extending a considerable distance into said combustion chamber, said body dividing said mouth into a primary draft passage communicating directly with 45 the forward portion of said combustion chamber, and a secondary draft passage com-

municating directly with said combustion chamber rearwardly of said primary passage; a body disposed above said mouth; and a plurality of nozzles carried by said last- 50 named body, said nozzles projecting vertically into said primary passage for supplying fuel thereto.

4. In a burner, the combination of: walls forming a combustion chamber, and a mouth 55 connecting said combustion chamber to the exterior; a body situated in said mouth, and extending a considerable distance into said combustion chamber, said body dividing said mouth into a primary draft passage 60 communicating directly with the forward portion of said combustion chamber, and a secondary draft passage communicating directly with said combustion chamber rearwardly of said primary passage; a body disposed above said mouth, said body having a 65 fuel chamber therein; and a nozzle carried by said last-named body in communication with said fuel chamber, said nozzle projecting into said primary passage for supplying 70 fuel thereto.

5. In a burner, the combination of: walls forming a combustion chamber and a mouth therefor; a flat septum plate extending rearwardly a considerable distance into said 75 combustion chamber for dividing said mouth into a primary draft passage communicating directly with the forward portion of said combustion chamber, and a secondary draft passage communicating directly with said combustion chamber rearwardly of said primary draft passage; and a fuel nozzle extending downward from a top wall of said mouth into said primary draft passage, in such a manner that the fuel issuing 80 therefrom mixes directly with air passing through said primary draft passage.

In testimony whereof, I have hereunto set my hand at Los Angeles, California, this 18th day of February, 1926.

MARTIN MADSEN.
